ERNEST YEOMAN ROBINSON, OF WITHTINGTON, ENGLAND

ANTENNA SYSTEM FOR WIRELESS COMMUNICATIONS

Application filed March 19, 1923, Serial No. 626,139, and in Great Britain May 5, 1922.

This invention relates to antenna for wireless communication such as for wireless telegraphy and telephony, and has for its object to provide an improved construction of the supporting structures or members of the antenna, whereby the antenna may be insulated in a more effective manner. The improved construction also eliminates, or reduces, to a minimum the losses incurred by stray currents which are normally induced in the supporting members such as the masts, guys, and the like.

The invention comprises the combination of an antenna supported by one or more members which are constructed in sections having insulating breaks interposed between them and means for electrically grading the sections of the structure so formed, in order that the structure may be electrically graded along its length.

The invention also comprises means for effecting this grading by adjusting the various electrical capacities of the sections of the supporting structure.

The invention further comprises means whereby the grading so produced by adjusting the various electrical capacities of the sections may be supplemented by, or replaced by connecting the sections to suitable sources of electromotive force.

Wireless antenna, as constructed at present, usually consists of a wire network, supported above the earth by suitable supporting members, such as towers or masts, which may be self-supporting or guyed. The antenna is attached to the masts by means of insulators, the said insulators taking up the whole of the voltage drop between the antenna and earth. According to this invention, a portion, or preferably the whole of the voltage drop may occur across insulators distributed along the length of the supporting structure.

For convenience, the present invention will be described with reference to antennæ which are supported by guyed masts, but it will be understood that the invention is equally and similarly applicable to all types of antenna supports and their components, such for instance as guys.

The objects of this invention, and the means

of attaining these objects, will be best understood with reference to the accompanying drawings in which Figs. 1 and 2 are diagrams representing the electrostatic field around an antenna, Fig. 3 is a diagrammatic representation of a sectionalized mast in accordance with the invention, Fig. 4 is a diagram illustrating voltage grading of a mast and Fig. 5 is an electric diagram of the approximate equivalent circuits of the antenna. Fig. 6 is a diagram illustrating a method of coupling the mast sections. Fig. 7 shows one form of mast construction in accordance with the invention, and Fig. 8 illustrates an antenna system in accordance with the invention.

In Figs. 1 and 2 the antenna is represented in section by a circular disc placed parallel to earth, but it will be understood that the invention is intended to be applied to any type or shape of aerial. In the following description the supporting members are referred to as masts and guys for convenience.

In Fig. 1, which illustrates the electrostatic field around the antenna when no masts, guys, or such like are present, the antenna is represented by the disc 1 which is connected to earth through the down lead 2. The electric field existing at any instant (say when the antenna voltage is a maximum) is represented in the conventional manner by equipotential lines 3. Fig. 2 illustrates the effect of a conducting supporting member or mast in proximity to the antenna. The mast is shown at 4 and the equipotential lines are indicated at 5. It will be seen that in the plane of the mast, the effect is to crowd the major portion of the lines into the space or gap 6 between the antenna and the mast top, thus resulting in said gap 6 being subjected to a very high electrical stress. This gap is very constricted and due to this fact and also to the fact that the insulators placed therein operate in an extremely exposed position, it is difficult to design insulators which are able to withstand the high potentials on the antenna, especially at the high frequency at which these potentials are produced.

Moreover, as hereinbefore explained, when the mast is constructed of electrically conducting material, currents which are sub-

stantially 180 degrees out of phase with the antenna current are induced in the mast, which mast currents decrease the efficiency of the antenna.

5 According to this invention, the mast is constructed in sections, the said sections being insulated from each other. The sections are electrically charged to definite potentials which potentials are alternating and substantially in phase with the potential on the antenna. The term potential as hereinafter used in connection with the mast structure, or the like, will mean that the potential is alternating, and in phase with that potential to which it is referred. It is arranged that the mast sections shall be at increasing potential as the antenna top is approached, so that the mast as a whole, is electrically graded along its length. By this means, the voltage at the 10 top of the mast may be between the voltage of the antenna top and earth, or preferably it may be at the voltage of the antenna itself. When the latter condition obtains, the antenna may be in direct connection with the mast 15 top, and the insulation between the mast and antenna top eliminated. The arrangement affords a simple and effective method of insulating the antenna; moreover, the mast currents are prevented and hence the mast 20 currents are prevented and hence the mast loss is eliminated.

When the mast is so constructed, and is graded along its length, it may be placed in proximity to the antenna without effecting the distribution of electrostatic field 25 round the antenna (except in the immediate neighbourhood of the sections) if it is arranged that the sections are electrically charged to the mean potential which the space they occupy would assume if the said 30 sections were not present. Similarly, the insulating breaks, since they prevent mast currents from flowing, will prevent the masts from affecting the distribution of magnetic field round the antenna. When the mast is 35 so constructed, insulation of the antenna may be effected entirely by means of the graded sections of the mast, the insulating breaks between these sections being suitably designed to withstand the voltages to which they are 40 subjected. The topmost section of the mast is preferably in electrical connection with the antenna; it is preferably arranged that the antenna top embraces the mast tops.

In Fig. 3 in which one mast is shown, the 45 mast is constructed of sections 7 which are insulated from each other by means of insulating breaks 8. The antenna is shown connected to the mast by means of the insulators 9 but these may be omitted as has been hereinbefore stated. The sections 7 may be charged electrically to suitable potentials in order to provide the required grading of the mast. In Fig. 4 two types of grading are shown. The curve 10 shows the type of grading 50 which may be employed so that radiation

from the antenna shall not be affected. In this case, the sections are charged to the mean potential which would exist in the space that they occupy. The curve 11 shows a uniform grading of the mast which is preferable when the mast is to be insulated for extremely high voltages in order that the voltage stress across the mast insulators may be similar and equal, that is to say, in order that the insulators may be equally stressed.

According to one method grading of the mast structure is produced by varying the electrical capacity of the structure sections to earth, to the antenna, and to each other; by suitably varying these capacities of the sections (hereinafter these individual capacities will be referred to as component capacities) any desired grading may be produced. For instance, a grading corresponding to curve 10 (Fig. 4) or a grading corresponding to curve 11 may be produced by suitably proportioning the component capacities. In Fig. 5 the component capacities are represented by the letter C with prefix and suffix numerals; those across the insulating breaks are denoted by the prefix 1, those between the sections and the antenna by the prefix 2 and those between the sections and earth, by the prefix 3. The suffix numerals denote the several sections of the mast and the corresponding component capacities. Capacity ${}_1C_1$ relates to the capacity of insulators 9 in Fig. 3. The diagram only illustrates the electrical circuit approximately. For accuracy, it would be necessary to represent the component capacities between sections which are not adjacent; it would also be necessary to consider the standing wave on the antenna. However, for the purpose of this description, it is sufficient to consider only the capacities referred to above. By varying these component capacities, the grading of the mast may be altered as desired.

The component capacities may be given the desired values by suitably proportioning the mast sections. The most important dimensions in this respect, are those of the section ends. The mast may also be graded by means of condensers connected from the sections to the antenna, to earth, and also connected between adjacent sections. In the preferred method, when condensers are employed, the adjacent section ends are connected to each other by means of condensers. These may consist of metal discs or the like situated on each side of the insulating break, or the condenser may be a separate unit connected electrically, and preferably mechanically, to the section ends. In the latter case, the condensers are preferably of the air dielectric type.

The grading produced by the component capacities of the sections may be supplemented by or alternatively substantially replaced by arranging that each section is connected

to a source of electromotive force in resonance with and preferably substantially in phase with the voltage on the antenna. This electromotive force for supplying the sections 5 may be suitably derived from the source supplying the power to the antenna. The sections may be energized for example by connecting them to the secondary of a transformer whose primary is coupled to the power source. In the preferred method it is 10 arranged that the sections are connected to tappings on an oscillation transformer which may be coupled to the antenna loading coil, or may be excited in any desired way. When 15 the antenna is excited by means of a high frequency alternator, the sections may be connected to tappings on the alternator windings.

Referring to Fig. 6, power is supplied along 20 leads 13 and the antenna is coupled thereto by means of a transformer formed by the windings 14 and 15. The exciting current passes through a winding 16 which is coupled to an oscillation transformer formed by an inductance 17 and capacity 19. The mast sections 7 are connected to tappings 20 on the transformer 16—17 as shown. When this arrangement is employed it is preferably arranged that the grading produced by the component capacities of the sections is equal and similar to the grading produced by means of the tappings of the oscillation transformer (if this is employed) in order that the oscillation transformer will not have to supply 25 an appreciable capacity or charging current to the said sections.

Inasmuch as it may not be possible to accurately grade the sections when these are graded by adjusting the component capacities 40 the most convenient method will be to grade the sections as accurately as possible by adjusting the component capacities and finally adjusting the grading by means of the tappings to the transformer, in which case 45 the charging current supplied by the transformer will only be that which is necessary to compensate for the inaccurate capacity grading of the sections.

When the mast is guyed, the sections there- 50 of may preferably be pin-jointed in order that no shear stress shall be placed on the section insulators.

Referring to Fig. 7, the top of one section 55 of a mast is shown at 21 and the bottom of the adjacent section thereof is shown at 22. Such sections are insulated from one another by means of the insulator 23 which preferably consists of porcelain, bakelite or the like. It is provided with a large rain shed 60 24 which may preferably be provided on its underside with corrugations or petticoats 25 in order to increase the length of the leakage path. Two metal supports 26 and 27 are fixed to the insulator 23 by means of suitable 65 material such as, for instance, lead, or a lead

alloy, so as to distribute the pressure on the surface of the insulator. The insulator faces and the corresponding supports 26 and 27 may be suitably corrugated as shown at 28 so as to key or interlock into each other. The metal support 27 is bolted or otherwise fixed to the top of the mast section 21. The support 26 has incorporated in it, or attached to it, a curved metal surface 29 on which the mast section 22 rests, the arrangement being 70 such as to provide a limited amount of relative movement between adjacent sections. Movement in a lateral direction may be prevented by means for example of a pin 30 on the curve surface 29 engaging in a corresponding recess 31 formed in the base of the mast section 22.

The guys must be insulated in a similar manner because the mast sections operate at high potentials. They are preferably insulated by means of link type insulators, such, for example as Hewlett insulators. They are distributed along the length of the guy and grading may be effected in the manner hereinbefore described.

The insulators between the mast sections (and also between the guy sections), may be provided with flash-over devices, such for example, as arcing horns in order to prevent a flash-over taking place on the surface of the insulator. When the condensers are connected across the section ends, the flash-over device may preferably be incorporated in the 90 said condensers.

In the antenna system shown in Fig. 8 the 100 antenna is supported by three sectionalized masts 4 which are constructed as hereinbefore described. Any desired number of masts may be employed. The masts are supported by guys such as 32 which are constructed in 105 sections having the insulating breaks therebetween, the whole being graded as hereinbefore described. For clearness of illustration only the guys attached to one mast are shown. The antenna consists of three box 110 shaped networks 33 which are suspended as shown between the mast tops and are in electrical connection with the latter. The down-lead is formed by the net work 34 as shown, connection to the antenna being preferably 115 made at the mid-points of the networks 33.

While the invention has been more particularly described with reference to antenna for wireless telegraphy and the like, it will be understood that it is not limited thereto 120 but may be employed for antenna for other wireless purposes, such as wireless transmission of power.

It will be understood that various modifications may be made without departing from 125 the scope of the invention.

I claim as my invention:—

1. A wireless antenna system embodying supporting members comprising sections which are insulated from one another and 130

have component capacities, and means for exciting them from sources of electro-motive force in synchronism with the antenna current, said component capacities and excitation being proportioned to jointly grade said sections electrically.

2. A wireless antenna system as claimed in claim 1, wherein the excitation grading is substantially equal to the capacity grading.

10 3. A wireless antenna system as claimed in claim 1, wherein the sections are excited by connection thereof with devices which are energized from and in synchronism with the source of antenna excitation.

15 In testimony whereof I have hereunto subscribed my name this 5th day of March, 1923.

ERNEST YEOMAN ROBINSON.
